To all whom it may concern:

Be it known that I, Melvin H. Boldt, a citizen of the United States, residing at Glenview, in the county of Cook, State of Illinois, have invented a new, original, and ornamental Design for a Refrigerator, of which the following is a specification, reference being had to the accompanying drawing, forming a part thereof.

In the drawing:

Fig. 1 is a front perspective view of a refrigerator in open position embodying my new design;

Fig. 2 shows to a reduced scale the front elevational view of the refrigerator with the door closed;

Fig. 3 shows to a reduced scale the left side elevational view of the refrigerator with the door closed; and

Fig. 4 shows to a reduced scale the top plan view of the refrigerator with the door closed.

The design for the refrigerator disclosed is characterized

by the internal portions having the configurations and appearances shown.

I claim:

The ornamental design for a refrigerator, as shown and described.
